DESIGN FOR A DRESS ENSEMBLE

Julia Richards, Brooklyn, N. Y.

Application October 11, 1940, Serial No. 95,774

Term of patent 3½ years

To all whom it may concern:

Be it known that I, Julia Richards, a citizen of the United States, residing at 1346 53rd Street, Brooklyn, in the county of Kings and State of New York, have invented a new, original, and ornamental Design for a Dress Ensemble, of which the following is a specification, reference being had to the accompanying drawing, forming part thereof.

Figure 1 is a front view of a dress ensemble, showing my new design;

Figure 2 is a front view of a dress alone;

Figure 3 is a rear view of the same; and

Figure 4 is a rear view of the jacket alone.

The characteristic feature of my design resides in the star-shaped braid embroidery on the front of the jacket member of the ensemble as shown, said jacket member having a V shaped neck with the collar of the dress member overlying the neck of the jacket in combination with the dress as shown.

I claim:

The ornamental design for a dress ensemble, substantially as shown and described.

JULIA RICHARDS.
